Specification of Letters Patent. Patented Dec. 30, 1919.

Application filed May 14, 1915. Serial No. 28,054.

To all whom it may concern:

Be it known that we, FRANK E. HOWARD and CHARLES P. HOWARD, citizens of the United States, and residents of Hartford, 5 in the county of Hartford and State of Connecticut, have invented certain new and useful Improvements in Hollow Doors and Fittings Therefor, of which the following is a full, clear, and exact specification.

This invention relates to improvements 10 in the construction and combination of hollow doors, windows and similar closure elements, and fittings therefor, and is herein shown as being particularly adapted for 15 steel door construction in which the doors, or at least the stiles thereof, are of hollow box-like form, made from sheet steel folded at the corners, sometimes combined with 20 panels of single plate or sheet thickness, the various sheets or folds being riveted or welded together. This box-like form of 25 door shell or stile makes a firm, stiff, fire-resisting structure, besides affording ample space within it for the various door fittings, such as hinges, latches, locks, or bolts employed 30 for suspending, operating and fastening the door. The problem, however, has been to utilize the inner cavities of the door shell, without injuriously cutting away 35 the door shell itself, for the introduction or removal of the fittings, and thus weakening the shell in the attempted utilization of its 40 inner chambers or spaces.

Another problem solved by the present invention is that of suitably locating and connecting together for operation within the door shell the various parts of door fittings which are widely separated in position, but connected together for operation, such as 45 the top and bottom locks or latches of the doors and their operating levers or handles which must or should be at an operating height or position convenient to the hand of the operator.

Moreover, the manufacture of doors and of the fittings therefor, especially latch and lock fittings, requires the employment of entirely different trades, methods and machinery, making it desirable to adapt the 50 door and its fittings for entirely separate

manufacture in different establishments, one manufacturing the doors and another manufacturing the fittings therefor, with suitable provision, however, for the subsequent easy assembling, firm attaching, and 55 correct functioning of the respective parts.

According to the present invention, these improvements are overcome by constructing the door and the fittings as entirely separate 60 units, each complete in itself as to its own construction, function and operation. The door fittings are mounted in complete connected and working condition upon the carrier, which is sufficiently extended to carry all of the desired parts correctly disposed at 65 their desired working positions, extending if necessary the full length of the longest door stile.

The door shell is constructed with an opening in the end of the stile, of a size only 70 sufficient to receive the largest cross-section of the door fitting unit, which is to be inserted therein. The carrier, after being inserted lengthwise through its entering aperture in the door shell, requires only to be 75 supported laterally by means of screws or similar fastenings, which necessitate only few and small apertures in the door shell, which thus retains a plain, smooth exterior appearance, and its maximum of strength 80 and stiffness.

Figure 1 of the drawings is an edge elevation, Fig. 2 a partial side elevation, and Fig. 3 a partial plan view, showing the plain unmutilated exterior appearance of a door 85 provided with these improvements. Figs. 4 and 5 are sectional elevations showing details of construction of the door and door fittings of which the exterior is shown in the previous figures, Fig. 4 being in section 90 taken on the line 4—4 of Fig. 5, while Fig. 5 is shown in section taken on the line 5—5 of Fig. 4. Fig. 6 is a side elevation partly in section showing the present invention applied to a flush type of door fittings. Fig. 95 7 is an edge elevation projected from Fig. 6, and in section taken on the line 7—7 thereof. Fig. 8 is a plan view in section taken on the line 8—8 of Fig. 6.

Fig. 9 is a side elevation partly in sec- 100

tion, and Fig. 10 a plan view projected from Fig. 6, also partly in section, showing another type of flush construction, and including a door pull and cushioned door edge. 5 Figs. 11, 12 and 13 show a similar flush construction with a further modified form of the door fittings. Fig. 11 is an edge elevation in section taken on the line 12—12 of Fig. 11. Fig. 12 is a side elevation, partly 10 in section taken on the line 12—12 of Fig. 11. Fig. 13 is a fragmentary edge view in section taken on the line 13—13 of Fig. 12.

In the embodiment of the invention illustrated in Figs. 1 to 5 inclusive, latch mechanism is employed adapted to latch the door at the top, and is provided with handles which project from the side faces of the doors. All of the interior latch mechanism is mounted and articulated in complete 20 working condition upon an extended flexible carrier, which is entered through an aperture in the top edge of the door shell, and extends longitudinally within the stile or shell of the door, adjacent to the front edge 25 of the door, being supported at suitable intervals in the length of the door by comparatively few locating abutments in the shell, and simple fastening devices, which are here shown as ordinary screws extending 30 through the door shell on one or both sides of the door and countersunk into the shell, flush with its surface.

The carrier is a flexible plate 5 provided with suitable studs, abutments, and guides 35 for accommodating the various parts. The plate is riveted or otherwise attached at its upper end to a base or frame 6, having a mortise 7 for guiding the upper end of the latch or bolt 8, and the flange 9 covers and 40 closes the aperture in the door shell 10 through which the carrier and its mechanism is inserted lengthwise. At suitable intervals in the length of the carrier plate, wherever lateral stiffness or fixity is needed, 45 studs or bosses 12, 13 are provided on the door shell or carrier, or both, which locate the carrier and its mechanism in suitable lateral position, and against which the carrier is held by means of screws 14 inserted 50 through one or both sides of the shell. To facilitate entering the carrier with its mechanism and guiding it to place past the abutments 12, or whatever reinforcements or other obstructions may be within the door shell, the leading end of the carrier is made 55 with inclined faces on one or more sides. In the particular embodiment here shown, the leading end of the carrier is a tapering or wedge shaped pilot 15, which may be 60 made integral with the carrier, or as herein shown be made in a separate piece and attached to the carrier plate by means of rivets or screws 16. As here shown the pilot piece 15 is made to serve also as a dis-

tance spacing member, to locate the plate in 65 sidewise position, being drawn against one of the abutments 12 by the fastening screws 14.

The particular form of the internal latch mechanism here shown constitutes no part 70 of the present invention and needs only brief description. The latch 8 may be beveled on one side to form a latch as here shown, or it may be square to form a dead bolt like that of Fig. 9. The bolt is fitted to 75 slide through the mortise 7 in the frame 6, its lower end being guided between studs or posts 19, the ends of which are secured to a bridge piece 20 between which and the carrier plate 5 the bolt slides freely. The bolt 80 is yieldingly pushed to its latching position by the spring 21 resting upon an abutment 22 secured to the carrier plate 5. Connection between the latch 8 and the operating 85 levers 23 of the door is made by connecting rods 24 and 25 coupled to the opposite ends of a reversing lever 26 on the stud 27 secured to the carrier plate 5. The upper end of the connecting rod 24 which may be integral with or attached to the latch 8 is here 90 shown as having a reverse L shaped head 28 engaging over a shoulder of the latch to allow the latter to be pushed down by its keeper in closing the door, without moving the connecting rods and their operating 95 handles.

A spring 31 resting upon the abutment 32 also secured to the carrier plate 5, serves to hold the connecting rods 24 and 25 yieldingly in the position shown in Fig. 5, with 100 the operating lever in its forward position against a pin 33 or any other suitable stop of the carrier plate 5.

The operating lever 23 is a bell-cranked member pivotally mounted upon the stud 34 105 secured to the carrier plate 5. The upper end of the lever 23 is slotted, to receive a connecting spindle 35, which projects from an operating handle 36 on the outer side of 110 the door, and where two of these handles are employed, as here shown, the spindle 35 extends entirely through from one handle to the other, and connects them firmly together.

The projecting operating handles 36 shown in Figs. 1 to 5 inclusive are mounted 115 on side plates 38 attached to the outer sides of the door shell 10. These side plates are preferably provided with posts 39 which project through apertures in the door shell or stile, and through or into corresponding apertures in the carrier plate 5, thus registering and doweling that portion of the carrier plate and its mechanism accurately 120 and firmly in position within the shell or stile. The plates are clamped together on 125 the opposite sides of the door by means of fastening screws 40 passing through the centers of the posts. These posts are to-

gether, or spacing members are provided within the shell to space the sides of the shell at a proper distance apart and prevent them from being buckled inwardly by the 5 screws.

The handles 36 are shown to be pivotally mounted at their lower ends upon studs or pivot pins 41 secured to or turning in the bosses 42.

10 By removing the fastening screws 14 and 40 and removing the side plates 38 with their handles and the spindle 35, the entire latch mechanism mounted upon the carrier plate 5 may be drawn endwise out of the 15 door stile, and be replaced with ease and certainty in its working position by reversing these operations.

Figs. 6 to 13 inclusive illustrate flush constructions which may be employed where 20 the door must be pushed entirely back into a partition or casing, or where for any reason the projecting handles 36 of the previous figures are not feasible or desirable. In these constructions the interior mechanism 25 of whatever nature, is mounted on a removable carrier plate substantially like that already described. To enable the door to be drawn out of its casing a door pull is provided which is also mounted on the removable 30 carrier. These figures also show the employment of a cushion or buffer on the edge of the door, to avoid injury to the clothing or person of passengers, or to keep out the weather. It will be understood that 35 any of these doors may be employed as single doors, closing against a jamb, or as double doors meeting at their edges.

In the construction shown in Figs. 6, 7 and 8, the interior latch mechanism is or 40 may be like that of the previous figures, mounted on a similar extended flexible carrier plate 51. The operating lever is, however, in this case, provided with two handles 52 and 53 disposed on opposite sides of 45 the carrier plate 51, which in this case is preferably made central with the door stile at this operating point, being bent or offset to this central position if necessary. The operating lever handles 52 and 53 are 50 pivotally mounted on the stud 54 secured to the carrier plate and these handles are connected together by the pin or stud 55 extending through the slot 56, which is elongated to allow of their swinging movement. This slot is covered as best shown 55 in Fig. 8 by side plates on opposite sides of the door shell, which side plates are deeply recessed at 60 to allow room for the fingers to enter from the side to operate the handles 60 52 and 53. These side plates may as illustrated in Figs. 6 and 7 be provided with posts 61 passing into or through the carrier plate and firmly supporting it laterally. The inturned flanges 62 of the side plates 56

and 57 may also bear against and support 65 the carrier plate, being slotted at 63 to receive the upper ends of the handles 52 and 53, and permit their swinging movement.

When desired, a lock of any well known form may be employed, the bolt of which 70 may be projected on either side of the upper end of the operating handles. When locked behind the handles, as in Fig. 6, they cannot be retracted to withdraw the latch 65. The handles may thus be locked even while 75 the door is in open position, since the latch, when loosely connected as in Fig. 5 will be depressed by its keeper and spring up again without moving the operating handles 52 and 53. When the handles are locked in 80 their drawn back position, the latch 65 will be held down, and will not engage with its keeper.

With these flush types of construction, having no projecting handles, a door pull 85 is frequently found desirable for drawing the door out of its casing or partition. Our improved door pull 70 is mounted on the removable carrier plate 71, as best illustrated in Figs. 9 and 10. The neutral inoperative 90 position of the pull is shown in Fig. 9 and its drawn out position is like shown in Fig. 12. The door pull 70 is pivotally mounted upon a stud 72 supported by the carrier plate 71, one end of the stud being carried 95 by the plate itself and the other end being carried by a bridge piece 73 supported on the plate 71 by the pivot stud 72, and by two other studs 74. The door pull is yieldingly held to its pivotal position and also at the 100 intermediate portion of its range of swinging movement on the pivot by means of a spring pressed device consisting of a swinging plate 75 pivoted at 76 to the carrier plate and provided with an abutment 77, the 105 ends of which bear against the door pull 70 above and below the pivot stud 72. The abutments and the swinging plate are yieldingly held in this position by means of a suitable spring 78 seated against the turned 110 down flange 79 of the bridge piece 73.

Thus the door pull is yieldingly held in the position shown in Fig. 9, projecting just far enough beyond the edge of the door or of the spring buffer 82 when such a buffer 115 is employed, to enable the pull to be grasped by the fingers and drawn out of the position shown in Fig. 12, thus enabling the fingers to take a better hold of the pull through the loop or eye 83 of the pull. The forward 120 swinging movement of the pull is stopped by bearing against the inner side of the door shell as at 84, while the door is being drawn out. As soon as the pull is released it is returned by its spring device to the position of 125 Fig. 9. When the door is closed against its jamb, or against a co-operating double door, the spring device allows the upper end of

the pull to be pushed backwardly flush with the edge of the door, to enable the door to close tightly.

The upper end of the pull is shaped and 5 adapted to the form of door and to suit the presence or absence of a buffer, being necessarily made longer when a buffer is employed, as herein shown.

When the width of the stile is sufficient to 10 enable the door pull to be folded back entirely within the stile, the door pull may be permanently pivoted to the carrier and thus be entered and removed from the stile with the carrier like the other parts. But where 15 the door stile is narrow, or for any other reason it is necessary or desirable to remove the door pull from the carrier before removing the latter from the stile, the pivotal connection is made as here shown, open at one 20 side. This permits the pull to be removed from the pivot pin, by drawing the pull outwardly to the position shown in Fig. 12, and then by means of the fingers or by means of 25 an ordinary wrench engaging the projecting portion of the pull, pushing the swinging abutment 77 back against the pressure of its spring 78 until the open side of the pivot seat is freed from the pivot, after 30 which the pull may be drawn out from the aperture 85 in the edge of the door, and be similarly replaced. To facilitate this replacement, the end of the pawl is preferably 35 made tapering at 86. The carrier in this case is also provided with a tapering pilot 87, like that of the previous figures.

The inner mechanism mounted upon the carrier 91, shown in Figs. 11 and 12, is a deadlocking mechanism in which the bolt 92 guided by suitable studs and abutments 40 on the carrier 91 is operated by any suitable tumbler mechanism, mounted between the carrier and the bridge piece 97, worked by a key through the key hole 93 or in any other well-known manner. No hand operated levers for this mechanism is shown; but side plates 94 having recessed sides 95 may be used as hand holes for closing and 45 opening the door. These side plates may similarly be provided with posts, which as 50 shown in Fig. 13 pass into or through the carrier and its associated mechanism to register and hold the carrier and its mechanism firmly to place within the door shell, as already described in connection with the side 55 plates shown in the previous figures.

It will be understood that the combinations illustrated in the drawings are merely suggestive of the various modifications which may be made, the parts being susceptible of combination in various machines for different purposes.

In assembling the latch or lock mechanism, it is only necessary to slide it with its carrier lengthwise through the stile from

the top, and then put the fastening screws 65 and side plates in position. Inasmuch as the latch mechanism is or may be completed, assembled and tested as to operation by the lock maker, no readjustment of the parts is usually necessary in connection with putting 70 it in position on the door.

It will be understood that the mechanism which is here shown as being applied to the top of the door may by suitable disposal or reversing of its parts be applied to the bottom of the door, or it may be applied in a horizontal position in any of the horizontal 75 stiles of the door, as for example when employed for locking a swinging door.

We claim as our invention:

1. The combination with a door having 80 a hollow stile, of a carrier extending longitudinally within the stile from one end thereof to a convenient operating height, remote from the end of the stile, and latch 85 mechanism, including a latch at the end of the stile, a lever at said convenient operating height, and connections between the lever and the latch, all mounted on the carrier in complete working condition, and removable 90 therewith as a unitary structure.

2. The combination, with a door having a hollow stile, of a carrier extending longitudinally within the stile from one end thereof to a convenient operating height, remote 95 from the end of the stile, and latch mechanism, including a latch at the end of the stile, a lever at the said convenient operating height, and connections between the lever and the latch, all mounted on the carrier in 100 complete working condition, and removable therewith as a unitary structure, and an operating handle mounted on an outer side of the stile, and connecting with the operating lever through the wall of the stile. 105

3. The combination, with a door of the described hollow shell construction, of door fittings and a flexible carrier on which the fittings are mounted in completely articulated condition, the carrier extending into 110 the door shell through an aperture in one face of the shell and closing the said aperture, the said carrier being provided with means for guiding the entering end of the carrier to its working position. 115

4. The combination, with a door of the described hollow shell construction, of a removable flexible carrier, articulated door fittings mounted in working position and condition upon the carrier, and extending within the door shell from one face thereof, fastening means for holding the carrier laterally in its working position between the inner walls of the door shell, the carrier being provided with a tapering pilot member for 120 guiding the carrier to its working position when assembling it with the door shell. 125

5. The combination, with a door of the de-

scribed hollow shell construction, of a removable flexible plate, latch mechanism mounted and articulated for complete working movement on the plate, all extending 5 within the door shell from one end thereof, locating members within the door shell for positioning the plate and its mechanism laterally within the shell, and fastening means extending through apertures in another 10 face of the door for securing the plate against said locating members.

6. The combination, with a door of the described hollow shell construction, of a carrier plate, latch mechanism, including an 15 operating lever therefor mounted in complete articulated working condition on the plate, all removably extending longitudinally within the door shell through an aperture in one face of said shell, an aperture 20 in another face of the shell for giving access to the said lever, and fastening means extending through a face of the door shell and holding the carrier within the door shell in working position, with the said lever accessible 25 through its said aperture in the shell.

7. The combination, with a door of the described hollow shell construction, a carrier plate, latch mechanism, including an operating lever therefor mounted in complete 30 articulated working condition on the plate, all removably extending longitudinally within the door shell through an aperture in one face of the said shell, an aperture in another face of the shell for giving access to the said operating lever, fastening means 35 extending through a face of the door shell for holding the carrier plate within the door shell in working position with the said lever, accessible through its said aperture in the shell, and a frame for said aperture provided with posts extending through relatively small apertures in the door shell and into the said carrier plate.

8. The combination, with a door of the 45 described hollow shell construction, of a carrier plate, latch mechanism, including an operating lever therefor, mounted in complete articulated working condition on the plate, all removably extending longitudinally within the door shell through an aperture in one face of the said shell, an aperture in another face of the shell for giving access to the said operating lever, fastening means extending through a face of the door 50 shell for holding the carrier plate within the door shell in working position with the said lever in operating relation to its said aperture in the shell, and a frame for said aperture provided with posts extending through relatively small apertures in the door shell, and through the said carrier, said posts being shouldered to locate the adjacent portion of the flexible carrier plate laterally between the inner walls of the door shell.

9. The combination, with a door having a hollow stile, of a carrier extending longitudinally within the stile through an aperture in the end of the stile, door fittings mounted in articulated working condition upon the carrier, and fastening means for the 70 carrier extending through a side wall of the stile.

10. The combination, with a door having a hollow stile, of latch mechanism, a carrier upon which the said mechanism is 75 mounted in working condition, all removably extending longitudinally within the stile through an aperture in the end thereof, and a side plate having lugs projecting into the stile to locate and support the carrier and its mechanism in working position.

11. The combination, with a door having a hollow stile, of latching mechanism, a carrier upon which the said mechanism is mounted in working condition, all removably extending longitudinally within the stile through an aperture in the end thereof, and side plates secured to the outer sides of the shell, and having lugs projecting inwardly to the carrier to center and support 90 the carrier in working position.

12. The combination, with a door having a hollow stile, of a door pull extending within the stile through an aperture, in the edge thereof, and mounted for swinging movement upon a pivot pin within the door stile, and means yieldingly holding the pull to an intermediate position in the range of its swinging movement, including a spring pressed device engaging the door pull at different sides of its pivot pin.

13. The combination, with a door having a hollow stile, of a door pull extending within the stile through an aperture in the edge thereof, and detachably mounted for swinging movement upon a pivot pin within the door stile, and means yieldingly holding the pull to an intermediate position in the range of its swinging movement, and also preventing it from being detached in its working operations, including a spring pressed device engaging the door pull at different sides of its pivotal support.

14. The combination, with a door having a hollow stile, of a door pull extending within the door stile through an aperture in the edge thereof and mounted for swinging movement by means of a pivot pin engaging with an open sided seat, and a spring pressed device yieldingly holding the pivot 115 and seat together whereby the pull may be detached from its pivotal connection against the pressure of the spring device and withdrawn through the said aperture.

15. The combination, with a hollow shell 125 door, of a removable carrier extending within the door shell through an aperture in the shell, door fittings mounted on the carrier

including a door pull extending through another aperture in the door shell, and detachably mounted for swinging movement on the carrier, and a spring pressed device also 5 mounted on the carrier and yieldingly engaging the door pull to prevent it from becoming detached during its working movements.

16. The combination, with a door having 10 a hollow stile, of a removable carrier extending within the door stile through an aperture thereof, and a door pull extending through another aperture in the stile, and detachably mounted within the stile

upon the carrier by means of an open sided 15 pivot joint, and a spring device including an arm pivotally mounted upon the carrier, and bearing against the door pull at different sides of its pivotal connection, yieldingly holding it at an intermediate portion of its 20 range of swinging movement and also yieldingly holding the pivotal connection together.

Signed at Hartford, Conn., this 13th day of May, 1915.

FRANK E. HOWARD.
CHARLES P. HOWARD.
